UNITED STATES PATENT OFFICE.

FREDERIC E. AHEARN, OF WOLLASTON, MASSACHUSETTS.

TEXTILE FABRIC FOR FRENCH-CORD SHOE BINDINGS AND OTHER USES.

Application filed June 29, 1927. Serial No. 202,233.

This invention relates to a woven textile fabric having selvages and other characteristic features adapting it to serve as a binding or finish, otherwise raw edges of a slipper or shoe; often called a "French cord" for the opening exposed for the entrance of the foot, for example.

The curved edges of this opening and other edges which may be bound are invariably not plane curves, and one object of this invention is to provide a sufficiently durable, well-finished and handsome binding strip which shall unite with mechanical strength and pliability in respect to longitudinal as well as transverse fold lines a minimum thickness of that part of the fabric lying interior of the upper margin of the shoe when in use, and a maximum compressibility and extensibility of that interior portion of the fabric, these characteristics still being consonant with manufacture by efficient and therefore relatively inexpensive modes of weaving. The qualities referred to are in aid of reaching flexibility both transversely and laterally to the plane of the woven fabric so that the binding may be smoothly applied without wrinkles to follow relatively sharp curves.

A further object of the invention is to provide a selvage structure for that part of the fabric intended to be exposed at the turn over the edges of the counter or vamp constituting the so-called French cord which shall be consonant with an effective surface texture or pattern of weave for this exposed portion of the fabric, and which will at the same time provide when turned in as usual over a sewed seam, a sufficient stuffing for the cord proper, as well as an exceedingly effective hold for the attachment stitches, which are usually in a machine-sewed seam uniting the facing leather or cloth and an interlining to the in-turned outer margin of the ribbon or tape of which the French cord structure is formed.

Another object is to provide in an integral strip fabric one longitudinally extending part or zone intended to go inside the shoe of such structure as not only to be longitudinally extensible and compressible, but to provide a selvage of little prominence, not thicker or very little thicker than the fabric flanking it, and well adapted either to be entered between the vamp or counter lining and the interlining and the outer face fabric or leather, and thus being adapted, if desired, to be cemented or otherwise fastened either between the interlining and the lining or within and over

the edge of the lining. A further object is to provide a narrow-ware integrally woven fabric having a grosgrain or Bengaline weave pattern side by side with the thin extensible and compressible fabric of the above-mentioned characteristics, and also having a thickened selvage of high tensile strength, which is adapted in use as an exterior edge reinforce of the shoe opening and cord stuffing.

I shall now describe the article of manufacture of the invention in connection with typical species only as shown in illustration of the genus of strip bindings in the accompanying drawings, in which:

Fig. 1 is a side elevation of a woman's shoe illustrating one use of the invention;

Fig. 2 is a slightly exaggerated face view of one face of the fabric;

Fig. 3 is a diagram plan view of a section of the fabric;

Fig. 4 is an exaggerated detail in elevation showing the construction of the fabric;

Fig. 5 is a diagram typical cross section;

Fig. 6 is a section on the line 6 of Fig. 4;

Fig. 7 is a section on the line 7 of Fig. 4;

Fig. 8 is a cross section through the edge of shoe parts showing a stage of the manufacture of the shoe;

Fig. 9 is a view similar to Fig. 8 showing the completed shoe; and

Fig. 10 is a view similar to Fig. 8 showing a modification.

Referring to Figs. 2, 3 and 4, the tape or ribbon 1 characteristically comprises a face section or zone 2 which may have any desirable pattern, shown as of the familiar grosgrain or Bengaline weave, having a thick, strong selvage structure 3, and being laterally flanked throughout the length and through any desirable proportion of the width of the fabric by a section or zone 4 thinner than the sections 2 or 3, and, desirably, relatively more compressible and extensible than section 2. Section 4 is provided with a selvage 5, the selvage 5 having little or no excess of thickness as compared with the thickness of the longitudinal section 4.

In order to produce any such fabric with good economy by usual operations on known instruments of manufacture, it is desirable that the weft extending transversely in reversed runs from selvage to selvage shall not be required to be different at one lateral part of the fabric from what it is at another lateral part of the fabric, so that the fabric may

be built up by regular picks of weft 9 laid alternately in opposite directions, for example, as lengths of the same weft yarn 9 carried by the same shuttle of any usual narrow-ware loom. For the more decorative part of the fabric, for example, the section 2 which is exposed in use, a preferred construction comprising a warp for the section 2 (and desirably for the section 3) of lustrous relatively 10 untwisted warp yarns; these typically are silk yarns 10 of low twist, or yarns of one of the artificial silks, or of any other strong highly lustrous textile fiber, for example, textiles such as ramie, polished or coated 15 flax, spun glass, or the like. With all of the warps in the section 2, the weft may be engaged by passing through each open shed twice in alternate directions before each beat-up thus to make the well-known grosgrain weave illustrated in Fig. 4, and shown 20 in warp-wise section in Fig. 6.

In the section 4 the wefts 9 are not laid twice in any one shed in the warps, but on the contrary, are engaged in a simple weave 25 formation with single-shed warps in said section 4, preferably in such a way as to obtain the expansible and compressible relation above mentioned; for example, the weave in this section of fabric may be a 60° twill as 30 illustrated, each warp passing over two wefts and under one in respect to one face of the fabric adjacent warps bearing the same relation with respect to one of the wefts of the first-mentioned pair and another weft. Many 35 other varieties of twill and sateen weaves provide a cloth of approximately the same characteristics and any of these weaves may be resorted to within the invention, if the structure is such as to result in a mere extensible and compressible fabric. In further 40 aid of compressibility and extensibility of the section 4, preferably the warps in that section are the warps 12, which, as indicated, may be twisted warp-yarns of good quality 45 and are of less width as they lie in the fabric than the widths of the warps 10. These qualities are such as follow from providing warps 50 for the section 4 of cotton, mercerized cotton, artificial silk, or, if desired, of linen or other well-spinning textile capable of making a uniform and flexible but strong yarn. The preferred material is a very flexible lustrously-mercerized cotton of the same color 55 as the warps 10.

It will be understood that because of the 60 weave structure the warps 10 spread where they round the virtual cord comprised of the doubled wefts 9, giving the cylindric form of the appearance of the transverse ribs characteristic of the grosgrain weave.

The thickened selvage section 3 may be woven in any desirable way, but it is sufficient to provide selvage warps 13 of relatively 65 heavier yarns than the warps 12. The warps 13 may be silk, artificial silk or cotton. The

shedding for four or more warp yarns at the section 3 is for a one-and-one weave as illustrated in Fig. 4. Preferably the spacing of the warps 13 is close, and the result of these provisions is to make the section 3 relatively 70 thick as compared with the section 2 or the section 4. On the contrary, the selvage 5 at the left-hand side of Fig. 4 of the preferably twilled section 4 is not much, if any, thicker than the body of section 4, and only two 75 warps 12 uniform with the warps of section 4 may be shed one-and-one to form this selvage.

In use, referring to Figs. 1, 8 and 9, the tape, strip or ribbon 1 may be applied with its 80 selvage edge 3 in registry with the cut edges of the facing leather or cloth 15 and interlining 14 of the vamps or quarters of the shoe S; because of its qualities above mentioned this strip may be freely flexed in the direction 85 of its own width to follow the sharp curves of this edge; and in this position may be sewed in place by a machine-sewed seam of stitches 16, Figs. 8 and 9. The tape or ribbon 1 is now turned, as indicated in one stage in 90 Fig. 8 and completed in Fig. 9, so that its portion 4 lines flush against the upper edge of the interlining 14, in which position the ribbon 1 may be held by cement either between it and the interlining 14 or between it and the 95 lining 17 of the parts of the shoe in question, the usual cement not being shown. The seam 16 may be any distance within and parallel to selvage 3; for example, as shown in Fig. 10, the selvage 3 may overlie the cut edges of 100 parts 14 and 15. Whatever the mode of fastening the interior lap 4 may be, the turn about the ultimate edge in the opening of the shoe is constituted of the portion 2 of the ribbon or tape 1 and is highly lustrous or otherwise decorative. Moreover, the thickened 105 selvage 3, being relatively inextensible, adds something as a stay to reduce expansibility of the shoe parts 14, 15, 17, and performs an office of decoration in holding the turn about 110 the edge of the parts 14, 15 to a rounder and more prominent figure.

Heretofore, so far as I am aware, the portions of ribbons or tapes employed for this purpose corresponding to the portion 4 of the 115 present device have either been thicker than the remainder of the ribbon or tape, or as little expansible or compressible as the remainder of the tape 1. This does not comport well with smoothly and accurately cementing down the 120 inner face of the French cord constituted of the tape or ribbon. By the present device, wrinkles and lumps are avoided by the readiness with which the relatively thin specially woven fabric section 4 conforms to the often 125 complex shape of the edge over which the ribbon or tape is folded in order to produce the French cord finish.

When the warp threads of the section 2 are made of artificial silk, one or more of the warp 130

threads of the selvage section 3 will preferably be of cotton for the reason that cotton threads are stronger than the usual artificial silk threads of the same size. A recommended structure is to make the two warp threads at the outside of the selvage section of cotton. This affords greater strength for stitching in the selvage section 3 than if all the warps in the selvage section were of artificial silk.

10 I claim:

1. Textile fabric for French cord shoe bindings and other uses having therein longitudinal extending integrally connected sections of fabric side by side, one of said sections 15 having a twilled weave-structure more extensible and compressible than the other, the other section having two or more runs of the weft common to both sections in each shed of the warps.

20 2. Woven fabric for an edge-binding having at least three longitudinally extending sections of different woven texture, increasing in thickness successively from one longitudinal selvage edge to the other, the thickest 25 fabric being at a selvage.

3. Woven fabric for an edge-binding having at least three longitudinally extending sections of different woven texture, increasing in thickness successively from one longitudinal selvage edge to the other, the thickest 30

fabric being at a selvage adjacent to a section characterized by multiple wefts in each open shed of warp, and adapted to serve as an anchorage for a seam and a stuffing for an overturned longitudinal corded fold.

35

4. Woven fabric for an edge-binding having at least three longitudinally extending sections of different woven texture, increasing in thickness successively from one longitudinal selvage edge to the other, the thickest 40 fabric being at a selvage adjacent to a section characterized by multiple wefts in each open shed of warp, and adapted to serve as an anchorage for a seam and a stuffing for an overturned longitudinal corded fold, the thinnest 45 section of fabric having a weave structure more adaptable for longitudinal extension or compression than said thickest section.

5. Selvaged narrow ware for shoe bindings having a longitudinally extending section of 50 twilled fabric with reversal of weft at a single warp for one selvage, and having an adjacent zone of fabric in which a plurality of wefts are engaged in each shed of the warp, said adjacent zone having a selvage including several 55 relatively thick warps.

Signed by me at Boston, Massachusetts, this 27th day of June, 1927.

FREDERIC E. AHEARN.
